New York

Application January 12, 1937, Serial No. 120,201

4 Claims. (Cl. 242—25)

This invention relates to a winding apparatus and more particularly to a take-up apparatus for strand handling machinery.

Certain types of coaxial conductor electric cables have an inner axial conductive strand surrounded by a tubular coaxial outer conductor, the two being held in coaxial relation by slotted disks of insulating material mounted transversely at intervals on the axial strand. In the manufacture of such cables, part of the procedure may be to apply the disks on the strand which is to be the axial conductor. It may then be desirable to wind up the disk bearing strand on a take-up reel for temporary storage or preliminary to some subsequent operation. It may not be practicable in winding such a disk bearing strand on a reel to use the familiar forms of distributors in which a guide, reciprocating along the axial direction of a take-up reel, shifts the strand laterally of itself to and fro over the barrel of the reel; for such a guide might well displace the disks on the strand or even strip them from it.

An object of the present invention is to provide an apparatus for taking up a strand in even and regular layers on a reel or the like without any guide member constraining the longitudinally advancing strand to move laterally.

One embodiment of the invention contemplates a take-up apparatus in which a take-up reel and motive means therefor are mounted together in a carriage reciprocable transversely of the natural path of the strand to be taken up, means being provided driven by the same motive means as the reel to reciprocate the carriage, and means being provided to ensure the linear speed of the carriage always being in a predetermined ratio to the rotary speed of the reel however either may vary.

Other objects and features of the invention will appear from the following detailed description of one embodiment of the invention taken in connection with the accompanying drawing in which the same reference numerals are applied to identical parts in the several figures and in which

Fig. 1 is a view in front elevation of a take-up apparatus constructed in accordance with the invention;

Fig. 2 is an enlarged view partly in section of a portion of the reel driving means; and

Fig. 3 is an enlarged sectional view on the line 3—3 of Fig. 1.

In the embodiment of the invention herein disclosed a strand 25 with disks 27 spaced thereon comes from some source not shown over a guide sheave 114.

From the sheave rim 114 the strand, bearing

its spaced disks, passes on to a take-up means adapted to coil it on a spool or reel 119. Because of the disks on the strand, using any of the customary reciprocating guide means to distribute the strand on the reel might disturb the disks on the strand. Hence in this apparatus means are provided whereby the reel may be reciprocated axially of itself and transversely to the strand. To this end the reel support and driving mechanism is mounted on a carriage 120 having rollers 10 or wheels 121 running on a stationary track 122. A rotatable shaft 123 is mounted in the bottom of the carriage parallel to the track and is provided with a reversely threaded portion 124 which engages a nut 125 immovably positioned between the rails. The nut, in place of a female thread, has a wedge ended spring pressed member 126 rotatably mounted in a bore therein, the wedge end being engaged in one of the threads 124 and the member 126 being rotatable to permit the wedge to turn from one thread to the other at their common ends.

The reel 119 is supported at one end on a cone wedge 127 journalled in the frame 120, entering the axial bore of the reel, and formed integrally 25 on a shaft 128 passing through the bore. A second cone wedge 129 is threaded on the other end of the shaft 128 to removably and adjustably enter the other end of the reel bore for supporting and gripping the reel. The extreme end of the shaft 128 outside of the cone 129 is supported in a corresponding axial hole in a friction drive disk 130 resiliently secured to a complementary disk 131 by bolts 132 and springs 133. A driving pin 134 rigidly mounted in the disk 130 enters a corresponding hole in the nearest head of the reel to drive the latter. Between the spaced disks 130 and 131 is a driving disk 135 integral with a collar 136 keyed to the power output shaft 137 of a speed reduction/gear 138 of any suitable construction driven by a motor 139, both the reduction gear and the motor being mounted on the frame 120. Annular friction members 140 and 141 are interposed between the disk 135 and the disks 130 and 131 respectively. The disks 130 and 131 are rotatably supported on the sleeve or collar 136 on anti-friction bearings. A sprocket 142 journalled on the shaft 137 is pinned to the disk 131 to be driven thereby and, in turn, drives the shaft 123 through a chain 143. A brake band 144 of any suitable material rides on a peripheral rim formed on the disk 131 and has one end attached to the frame 120 by any appropriate means not shown and is tensioned by a removable and interchangeable weight 145.

In operation the take-up reel 119 is driven in continuous rotation by the motor 139 through the reduction gear 138 and the friction clutch 135, 140, 141, 131, 130. This friction clutch is 5 adjusted by means of the bolts 132, to slip in proportion as the diameter of the wound material on the reel increases, thus keeping the linear speed of take-up substantially constant. The reel and its drive are traversed to and fro across 10 the direction of take-up by the sprocket 142, chain 143, shaft 123 and nut 125, to distribute the strand being taken up in even layers on the spool. It will be noticed that the traversing means is driven from the driven member 131 of 15 the clutch, and that therefore the speed of traverse of the spool is always proportional to its speed of rotation.

The embodiment of the invention herein disclosed is illustrative only and may be modified 20 and departed from in many ways without departing from the spirit and scope of the invention as pointed out in and limited solely by the appended claims.

What is claimed is:

25 1. A strand winding apparatus comprising a reciprocable carriage, means on the carriage to support a rotatable reel, means on the carriage to drive the reel in rotation, means on the carriage to drive the carriage in reciprocation, and means to cause the linear speed of the carriage to be in a constant ratio to the rotary speed of the reel.

2. A strand winding apparatus comprising a reciprocable carriage, means on the carriage to

support a rotatable reel, a rotatable member on the carriage positively coupled to the reel to drive the same, motor means on the carriage slippably coupled to the member to drive the same, means on the carriage to drive the carriage in reciprocation, and means to couple the member positively to the carriage driving means to drive the same. 5

3. A strand winding apparatus comprising a reciprocable carriage, means on the carriage to support a rotatable reel, means on the carriage to drive the reel in rotation, means on the carriage to drive the carriage in reciprocation, and means to drive both the reel in rotation and the carriage in reciprocation at unvarying relative 15 speed and slippably variable absolute speed.

4. A strand winding apparatus comprising a fixed track transverse to the normal path of a strand to be wound, a carriage reciprocable on the track, means to rotatably support a reel on 20 the carriage with the axis of the reel parallel to the track, a rotatable member to be positively coupled to the reel to drive the same, a rotatable clutch member to be slippably coupled to the reel driving member, a motor mounted on the 25 carriage to drive the clutch member, a rotatable screw threaded shaft mounted on the carriage and coupled to the reel driving member to be driven thereby, and a member engaging the thread of the shaft and stationarily mounted 30 with respect to the track to drive the carriage.
